UNITED STATES PATENT OFFICE.

ARCHIBALD HENRY FRANCIS COTTRALL, OF SPRINGFIELD, MISSOURI,
ASSIGNOR OF TWO-THIRDS TO ORVAL J. ANDREWS AND HERBERT
A. KNIGHT, OF SPRINGFIELD, MISSOURI.

RAILWAY BRIDLE-ROD.

SPECIFICATION forming part of Letters Patent No. 758,421, dated April 26, 1904.

Application filed July 25, 1903. Serial No. 167,056. (No model.)

To all whom it may concern:

Be it known that I, ARCHIBALD HENRY FRANCIS COTTRALL, a citizen of the United States, residing at Springfield, in the county of Greene and State of Missouri, have invented new and useful Improvements in Railway Bridle-Rods, of which the following is a specification.

My invention relates to improvements in bridle-rods for railway-switches, the object of 10 which is to provide a simple, convenient, firm, and durable device for quickly and easily adjusting the width of the points of switches. These objects I obtain by means of the device illustrated in the accompanying drawings, 15 forming a part of this specification, in which—

Figure 1 is a view in elevation of the entire device. Fig. 2 is an enlarged view of one end of the bridle-rod. Fig. 3 is a longitudinal vertical sectional view of Fig. 2.

Similar letters indicate corresponding parts in the several figures.

A is the main bridle-rod, provided with teeth or notches A² near each end for receiving similar notches B² and C² in the adjustable pieces 25 B and C. Said adjustable pieces B and C are provided with two or more clamping-bolts for holding the adjustable parts firmly to the main bridle-rod A. Said bolts D, E, and F are preferably provided with squared shoulders to prevent their turning where they pass 30 through the main bridle-rod, and for the purpose of adjustment the main bridle-rod A has a slot A³ near each end, in which the bolts D and E work back and forth, and the adjustable pieces B and C are provided with slots B³ and C³, which permit the adjustable part 35 to receive the bolt F to slide back and forth. Said bolts are provided with nuts D², E², and F² and with suitable washers D³, E³, and F³. Said washers may be any desired kind, preferably a spring or nut-lock washer, to prevent 40 the nuts from turning off.

By this device I adjust the points of the rail at the switch to the desired width by loosening the nuts D², E², and F² and moving the

adjustable piece back and forward on the main bridle-rod, and for adjusting the opposite end the movable piece C is operated in the same way. By this construction I can change either end of the bridle-rod so as to adjust either 50 one of the tracks without taking up or removing the main bridle-rod, which is attached to the switch-lever.

Having thus described my invention, what I claim as new, and desire to secure by Letters 55 Patent of the United States, is—

1. Combination of an adjustable bridle-rod having notches for engaging movable plates, and holes and slots for receiving bolts combined with movable plates having notches for 60 engaging the bridle-rod, holes and slots for receiving and adjusting connecting-bolts, and connecting-bolts provided with nuts and locking-washers for holding the same in position shown and described for the purpose specified. 65

2. An adjustable bridle-rod consisting of a main part or rod provided with notches for engaging sliding plates, and holes and slots for receiving adjusting-bolts, combined with adjustable sliding plates near each end, said 70 plates being provided with notches for engaging the main rod, and holes, and slots for adjusting-bolts, and bolts for securing the parts in the desired positions substantially as shown and described. 75

3. The combination in a bridle-rod of a main rod, and two movable attachments or parts, one near each end for adjusting the width of switch-points of railway-rails, said movable parts having slots, and holes for bolts and 80 bolts provided with locks for securing the same in position, substantially as shown and described.

In testimony whereof I have signed my name to this specification in the presence of two sub- 85 scribing witnesses.

ARCHIBALD HENRY FRANCIS COTTRALL.
